FOREIGN PATENT DOCUMENTS

GB 6185412 * 1/2022

Primary Examiner — Joseph Kukella*Assistant Examiner* — Darryl J Dardenne(74) *Attorney, Agent, or Firm* — Bochner IP, PLLC;
 Andrew D. Bochner(57) **CLAIM**

The ornamental design for a roulette tumbler, as shown and described.

DESCRIPTION

FIG. 1 is a top, front, right side perspective view;
 FIG. 2 is a front elevation view thereof;
 FIG. 3 is a rear elevation view thereof;
 FIG. 4 is a left side elevation view thereof;
 FIG. 5 is a right side elevation view thereof;
 FIG. 6 is a top plan view thereof;
 FIG. 7 is a bottom plan view thereof; and,
 FIG. 8 is a cross-section view taken along line 8-8 of FIG. 4, shown at an enlarged scale.
 In the drawings, the broken lines are for the purpose of illustrating environment only, and form no part of the claimed design.

1 Claim, 5 Drawing Sheets(56)
